(57) **CLAIM**

The ornamental design for a combination handheld delivery device and controller unit, as shown and described.

DESCRIPTION

FIG. 1 is a perspective view of a combined handheld delivery device and controller unit showing our new design; FIG. 2 is a top view of the handheld delivery device, the controller unit not shown;

FIG. 3 is a bottom view of the handheld delivery device;

FIG. 4 is a first side view of the handheld delivery device;

FIG. 5 is a second side view of the handheld delivery device;

FIG. 6 is a front view of the handheld delivery device;

FIG. 7 is a back view of the handheld delivery device;

FIG. 8 is a perspective view of the controller unit as attached to a user's wrist, the handheld delivery device not shown;

FIG. 9 is a top view of the controller unit;

FIG. 10 is a bottom view of the controller unit;

FIG. 11 is a front view of the controller unit;

FIG. 12 is a back view of the controller unit; and,

FIG. 13 is a side view of the controller unit, the opposing side being a mirror image thereof.

The broken lines depicting the connection apertures in FIGS. 7 and 11 represent the bounds of the claimed design while all other broken lines are directed to environment and are for illustrative purposes only; the broken lines form no part of the claimed design.
